UNITED STATES PATENT OFFICE.

DENNIS PARKS, OF ST. LOUIS, MISSOURI.

MACHINE FOR GOUGING HEEL BLANKS.

Application filed January 5, 1923. Serial No. 610,793.

This invention relates to the art of gouging heel blanks and has for its general object the provision of a machine for this purpose which shall operate with reliability and 5 accuracy to gouge heel blanks successively supplied thereto to a definite depth and with the desired conformation over a defined area of each heel blank.

For the attainment of this general object 10 I have provided a machine shown in the accompanying drawings, which is characterized by novel means for feeding a heel blank to the correct position to be gouged; by a novel reciprocating gouging mechanism; by 15 novel means for forcing the heel blank into engagement with the gouging knife in timed relation to its stroke whereby to insure a gradual tapering incision of the surface of the heel blank by the gouging knife; 20 by the provision of a stationary face plate through which the gouging knife projects, and against which the heel blank is pressed during the gouging operation, whereby the limit of the incision of the heel blank by the 25 gouging knife is rendered fixed and invariable; by novel means for co-ordinating the movements of the gouging knife and the pressure device for forcing and maintaining the heel blank in engagement therewith during 30 the gouging operation; by a novel cutting block of wood or similar material having its edge in exact alignment with the plane of the cutting edge of the gouger; by novel means for restraining the movement 35 of the heel blanks through the machine to prevent the heel blank being fed to the gouger from being thrown past the position it should occupy to be gouged; and by novel means for rendering the heel blank pressing 40 device both yielding and adjustable.

In the accompanying drawings—

Figure 1 is a view in broken side elevation illustrating a machine constructed according to my invention;

Figure 2 is a broken top plan view of the same on an enlarged scale;

Figure 3 is a view in front elevation of the machine, the lower portion of the standards being broken away; and

Figure 4 is a central longitudinal sectional view of the front portion of the machine taken on the line 4—4 of Figure 2.

Referring now to the drawings, the numerals 1 and 2 indicate respectively a front 55 and rear frame-support, supported on the top, and at either side of which are wooden

beams or sills 3 and 4. Mounted on and extending between these beams is a bin 5 for holding heel-blanks. The beams 3 and 4 project slightly beyond the front frame-support 1, and secured on and extending between the forward ends of these beams is a metal cross-beam 6 having on its outer edge a vertically disposed flange 7 and providing centrally of its length a vertically disposed 60 housing 8. Slidably mounted in the front portion of the housing 8 to reciprocate in a vertical plane is a slide-bar 9, which is rectangular in general outline and hollow or three-sided, and the face of the front side 65 10 of which is flush with the face of the flange 7, as shown more particularly in Figure 2. Near the top of the slide-bar 9 on the inner side of the front wall 10 thereof (Figure 4) and on either side thereof are 70 inclined abutments 11, which terminate in the upper edge of a transverse slot 12 provided in the front wall 10 of the slide-bar 9. The lower edge 13 of slot 12 (Figure 3) is curved to conform to the curvature of the 75 cutting edge at the lower end of a gouger 14 (Figure 4), which cutting edge projects beyond the face of the front wall 10 of the slide-bar to a greater or less extent, as the 80 gouger may be adjusted for the depth of 85 gouge required. The abutments 11 are provided with screw-threaded apertures on their rear side, and the gouger 14 is applied to the rear face of these abutments and secured in position by means of a clamp block 90 15, having apertures through which screws 16 are inserted and screwed into the apertures of abutments 11.

The upper end of the clamp block 15 is 95 provided with a shoulder 17 which extends over the upper end of the gouger 14 (Figure 4). This shoulder is provided with a central screw-threaded aperture to receive an adjusting screw 18, the lower end of which bears against the top of the gouger 14. The 100 gouger is slotted, as will be understood, to pass over the screws 16, and by turning down the set screw 18, the cutting edge of the gouger may be caused to project any desired 105 distance beyond the face of the front wall 10 of the slide-bar. Ordinarily, the adjustment of the gouger is only required in initially placing it in position. If, however, it is desired to withdraw the gouger to make 110 a less depth of gouge in the heel-blank, it is necessary to unscrew the set screw 18 and loosen screws 16 so that the gouger may be

pushed inward, after which the set screw 18 is turned in engagement with the gouger, and the screws 16 tightened.

The cutting edge of the gouger 14 co-
5 operates with the cutting block 19, which is inserted in a recess 20 of a socket member 21 (Figure 3) provided centrally of a casting 22. In order to secure an exact cutting alignment between the edge of the gouger and
10 the co-operating or inner edge of the cutting block 19, I preferably use a cutting block of hard wood of a width, initially, to project under the cutting edge of the gouger. I then operate the machine to cause the
15 gouger to descend, with the result that it slices from the inner side of the cutting block the portion thereof projecting beneath the gouger, thereby insuring the closest adjustment between the cutting edge of the
20 knife and the co-operating edge of the cutting block.

The casting 22 is provided on opposite sides of the socket member 21 with integral lateral extensions 23, the inner faces of
25 which are flat to lie flush against the front face of the upwardly extending flange 7 (Figure 3), and the upper sides of which form continuations of, or are in a plane with, the top of the socket member 21. The
30 top of the cutting block 19 is also flush with the top of the socket member 21 and the upper sides of the extensions 23 so that a continuous flat support is provided for the heel-blank throughout the length of the upper
35 side of the casting 22, that is, from one end of one extension 23 to the end of the other extension 23. I prefer to make the casting 22 bearing the cutting block 19, and the top of which casting forms a support, as stated,
40 for the heel-blanks to be operated upon, vertically adjustable. To this end, on either side of the socket member 21 (Figure 3), I provide in the casting vertically disposed slots 24, through which screws 25 are inserted and screwed into screw-threaded apertures, provided in the flange 7. By
45 loosening these screws, the casting 22 may be raised or lowered, as will be understood. For reciprocating the slide-bar 9, I provide
50 the following mechanism:

Mounted in suitable bearings in the supports 1 and 2 is a counter shaft 26 which is normally idle. The inner end of this counter shaft projects beyond the support
55 2, and has secured thereon a pinion 27, which is in mesh with a gear 28, secured on the outer end of a driven shaft 29, also mounted in the supports 1 and 2. Beyond the pinion 27, the counter shaft 26 has slidably mounted thereon a clutch sleeve 30, on which is mounted a pulley 31, which is driven by a belt 32 from any source of power. On the inner end of the counter
60 shaft 26, there is fixedly secured a clutch member 33 which is designed to have the

clutch member 30 moved into engagement therewith. To this end, the sleeve 30 is provided with a flanged collar 34, which is engaged by the bifurcated end of a lever 35 pivotally mounted at 36 on a support 37 provided at the rear of the machine. By moving this lever in one direction or the other, the clutch members 30 and 33 may be engaged or disengaged at the will of the operator. When in engagement, the counter shaft will be driven and thereby, through pinion 27 and gear 28, rotate the driven shaft 29. The counter shaft 26 is preferably provided on its extreme inner end with a hand-wheel 38 to permit the counter shaft 26 to be turned manually when setting up or adjusting the parts of the machine.

The bearing for the outer or front end of the counter shaft 26 is shown at 39 in Figure 4, and is preferably provided on a frame member 40, secured on the support 1. The lower end of this frame member provides a bearing 41 for the outer or front end of the driven shaft 29, which end projects through and beyond said bearing and has fixedly secured on it a cam disk 42, having one side cut away on a curved line, as indicated at 43. The circular side 44 of this cam disk acts as a cam for a purpose to be presently described. Secured in the cam disk 42 is a crank arm 45 which projects some distance beyond the outer face of the cam disk, and has secured on its outer end a cam wheel 46 provided at one portion of its outer face with a cam surface 47. Pivotally mounted at its lower end on the crank arm 45, is a pitman rod 48, the upper end of which is pivotally mounted on a stud 49 secured in and projecting from the rear of the front wall 10 of the slide-bar 9. When the clutch members 30 and 33 are in engagement, the rotation of shaft 29 will cause the rotation of the cam disk 42, and thereby the reciprocation of the slide-bar 9 by the pitman rod 48. A guard 50 extends over the connection between the upper ends of the pitman rod 48 with the stud 49 to protect the bearings from shavings, dust, and the like, resulting from gouging the heel-blank.

In the operation of the machine, means are provided for moving the heel-blank into a position to be gouged in timed relation with the movement of a pressure device which operates to force the heel-blank against the cutting edge of the gouger. These mechanisms will be described in order.

The device for feeding the heel-blanks into position comprises an arm 51 (Figures 1 and 3) pivotally mounted on a stud 52 projecting from a bracket 53 mounted on a member of the support 1. At a suitable distance from its lower end, the arm 51 has pivotally mounted thereon on a stud 54 an anti-friction wheel 55 which is in line with

and adapted to be engaged by the cam surface 44 of cam disk 42. The outer side of the arm 51 is longitudinally recessed to receive the lower end portion of a throw-arm 56 which is secured on the arm 51 by means of screws 57. At its upper end, the throw-arm 56 has secured thereon a stud 58 (Figures 1, 2 and 3), which is adapted to seat in a recess 59 provided on the upper side of a feed-plate 60, which rests upon the upper flat side 61 of the casting 22, and is adapted to slide back and forth thereon in frictional engagement with the flat face of the flange 7, by which it is guided. Secured 5 toward the forward end of the throw-arm 56 is one end of a coil spring 62, the other end of which is secured to the sill 4. It will readily be seen that as the cam disk 42 rotates when the cam surface 44 engages the 10 wheel 55, the arm 51 and throw-arm 56 will be moved outward against the resistance of spring 62, thereby moving the feed-plate 60 outward, or to the left, as shown by the dotted lines in Figure 3. When the cam surface 25 44 passes off of the wheel 55, the spring 62 will draw the throw-arm toward the right, at which movement the heel-blank inserted in front of the feed-plate will be moved by the latter to a position opposite the gouger 14. The inward movement of the throw-arm 56 is gradual, due to the conformation of the cam disk 42, and this movement is arrested by means of a set screw 63 carried by the throw-arm, the inner end of which 30 35 is adapted to come in contact with the edge of a casting 64 depending from the front of the cross-beam 6. By loosening the lock-nuts 65 on the set screw 63, the latter may be turned in one direction or the other to adjust the extent of the inward movement of the throw-arm 56, as will be understood. The mechanism for pressing the heel-blank into engagement with the gouger 14 and the face of the wall 10 of the slide-bar 9 will now 40 45 be described, referring particularly to Figures 3 and 4.

Cast on the front of the socket member 21 are two lugs 66 which are provided with apertures to receive a pin 67 passed there-through and through an aperture 68 in a relatively heavy head 69, the aperture 68 being located to one side of the longitudinal center of the head 69, that is, toward the side of said head nearest the machine, for a purpose to be presently described. The lower end of the head 69 is provided with a recess 70 which is adapted to receive the upper end of a bar 71, which is secured in the head by means of a clamp-screw 72.

Mounted on the lower end of the bar 71 is a roller 73 which is held by gravity in contact with the cam wheel 46 by reason of the overbalancing of head 69, due to the location of the aperture 68. Projecting upward 50 55 60 65 70 75 80 85 90 95 100 105 110 115 120 125 130 from the head 69 is an arm 74 which has at its upper end a reduced portion 75 affording shoulders 76 on either side thereof. The reduced portion 75 forms a rib, on which is mounted to slide on the shoulders 76 a bar 77 having a longitudinal slot 78 for receiving said rib. A plate 79 is applied to the top of the rib 75 and secured thereon by a screw 80 for holding the bar 77 in position on the arm 74. The outer end of the bar 77 is provided with a depending portion 81 which is 75 80 85 90 95 100 105 110 115 120 125 130 provided with an aperture to receive the smooth portion 82 of a rod, having a screw-threaded end 83 engaging in a screw-threaded aperture provided in the arm 74. Between the smooth portion 82 and the screw-threaded portion 83 of said rod, there is a shoulder 84 which bears against the inner side of the projecting portion 81 of bar 77. On the outer end of the smooth portion 82 there is secured a knurled head 85 for turning the screw-threaded member 83, and between the head 85 and the projection 81 is located a coil spring 86 which normally presses the projection 81 into engagement with the shoulder 84.

Mounted on the outer end of the bar 77, adjacent to the front of the slide-bar 9 is a pressure-plate 87 having a flat side 88 for exerting pressure against the heel-blank. As it frequently happens that the heel-blanks to be gouged are of the "decked" variety in which, as is known, the surfaces of the top and bottom lifts are inclined toward each other, I provide in the face of the pressure-plate 87 an inclined recess 89 100 for receiving the smaller or tread end of the decked heel-blank, so as to compensate for the difference in inclination alluded to and permit the top and bottom of the heel-blank to lie flush against the surface of the bottom of the recess 89 and the front face 10 of the slide-bar 9 respectively. Thus, a direct pressure can be exerted over the whole surface of the top or tread lift of a decked heel-blank by the pressure-plate. In other forms of heel-blanks, the size of the lifts is such as to extend beyond the edges of the recess 89, as shown in Figure 4, where the heel-blank is indicated by the numeral 90, and the recess does not affect the pressure operation.

In operation, the heel-blank that is being gouged is removed by the heel-blank which is being fed into position to be gouged. I provide for retarding the movement of two or more of the heel-blanks that have been 120 125 130 gouged, as they are progressively forced laterally from in front of the gouger, in order to prevent the heel-blank which is fed into position from being moved by inertia past the correct position opposite the gouger. To this end, I secure on the side of the pressure-plate at which the gouged heel-blanks are discharged, which is at the right of the machine as shown in Figure 3, a leaf-spring 91, the inner end of which is preferably se-

cured to the pressure-plate 87 by means of screws, or the like, 92. The outer end of said leaf-spring is free and normally bears against the face of the flange 7. From an inspection of Figures 2 and 3, it will be seen that as the heel-blanks are forced over the top 61 of the casting 22, they will be engaged by the spring 91, which will exert sufficient pressure on them to prevent any movement 10 after the feed-plate 60 has moved a fresh heel-blank to position in front of the gouger. In other words, each new heel-blank is moved by the feed-plate 60 to a position opposite the gouger, and two, three, or more 15 of the gouged heel-blanks are bodily moved forward by the movement to the gouging position of the fresh heel-blank, such movement being against the frictional resistance of the spring 91. The operation of the machine in its entirety is as follows:

The belt 32 running, the lever 35 is moved inward to place the clutch member 30 into engagement with the clutch member 33, thereby revolving the counter shaft 26, 25 which, through engagement of pinion 27 with gear 28, rotates shaft 29. This latter shaft causes the rotation of cam disk 42 and cam wheel 55 in unison. As the cam surface 44 of the former engages the cam wheel 55, the arm 51 and throw-arm 56 are moved outward, or toward the left in Figure 3, carrying the feed-plate 60 with it. During this initial movement, the roller 73 is opposite the plain surface of cam wheel 46, being 30 swung to that position by the overbalancing of head 69, due to the weight of material beyond the pivot pin 67. The operator then places a heel-blank in front of the feed-plate, and as the cam surface 44 moves out of engagement with cam wheel 55, the spring 62 draws the throw-arm 56 inward, or toward the right in Figure 3, until this motion is arrested by engagement of the end of screw 63 with the casting 64. This movement results in positioning the heel-blank 90 in front of the gouger 87. The cam surface 44 again engages the cam wheel 55 in the rotation of the cam disk 42 and again moves the feed-plate outward. The parts are so arranged that when the feed-plate has passed from in front of the pressure-plate 87, the cam surface 47 of cam wheel 46 will then engage roller 73, and, by throwing the lower end of rod 71 outward, move the arm 74 inward, or toward slide-bar 9, and the pressure-plate 88 into engagement with the heel-blank 90. The position of the crank 45 with reference to the cam surface 47 is such that the pitman rod 48 is drawn downward by the crank in the rotation of cam disk 42 practically simultaneously with the exertion of pressure by the pressure-plate 88 on the heel-blank. The resultant of these two movements, that is, the inward movement of the heel-blank in a horizontal plane and the downward move- 55 60 65

ment of the gouger in a vertical plane, causes the gouger to make an inclined or tapering incision in the heel-blank for a certain distance, determined by the adjustment of the gouger, and after the heel-blank is 70 pressed into engagement with the face of the slide-bar 9, the continued movement of the gouger makes a cut of uniform depth to the breast edge of the heel-blank, the cutting edge of the gouger passing below the surface of the cutting-block 19. Due to the fact that the cutting edge of the gouger is in such close proximity to the inner top edge and side of the cutting-block 19, the gouger will make a clean cut at the breast edge of 80 the heel-blank. The position of the parts as they appear after the heel-blank has been gouged is shown in Figure 4.

It will be understood, of course, and as indicated by dotted lines in Figure 3, that the cutting edge of the gouger is curved so that the material is removed from the heel-blank in a curved line to make a curved recess in the heel-blank. In the continued rotation of shaft 29, the slide-bar 9 with the 90 gouger will be raised, the cam surface 47 will pass from under roller 73, allowing the same to swing inward to move the pressure-plate 88 away from the heel-blank, and the cam surface 44 will pass off of cam wheel 95 55, allowing the spring 62 to draw the throw-arm 56 inward, thereby moving the fresh heel-blank, which has been placed by the operator in front of the feed-plate 60, to a position opposite the gouger 87. As the new 100 heel-blank is thus moved into position, it forces the previously gouged heel-blank to one side and under the leaf-spring 91, in the manner indicated by dotted lines in Figure 3. The succeeding operations of the machine are repetitions of the operation just described.

The machine shown in the accompanying drawings and above described represents an actual, and the preferred, embodiment of my 110 invention. I wish it understood, however, that the broad principle of the invention could find its embodiment in machines otherwise constructed than that herein shown, but I therefore do not wish to be limited in the 115 interpretation of the claims to the precise details of construction shown and described.

I claim:

1. A machine for gouging heel-blanks comprising a support, a member slidably mounted therein and having a gouger projecting from its front face, means for forcing the heel-blank against said gouger and the front face of said member and in a direction at right angles to the plane of movement of the gouger, and means for reciprocating said member. 120

2. A gouging machine comprising a support, a slide-bar mounted therein having a flat front face, a gouger carried by said bar 130

and projecting beyond said front face, means for feeding a heel-blank to a position in front of said gouger, means for reciprocating said slide-bar, and means for forcing 5 the heel-blank into engagement with the gouger and the front face of said slide-bar and in a direction at right angles to the plane of movement of the gouger.

3. A gouging machine comprising a support, a slide-bar mounted therein for vertical movement, a gouger carried by said slide-bar and projecting from the front face thereof, means for reciprocating said slide-bar, and means for forcing the heel-blank into engagement with the gouger and the front face of said slide-bar and in a direction at right angles to the plane of movement of the gouger, said means being co-ordinated to cause exertion of pressure on the heel-blank 15 substantially simultaneously with the downward movement of the gouger.

4. A gouging machine comprising a support, a slide-bar mounted therein for vertical movement, a gouger mounted in said 25 slide-bar and projecting from the front face thereof, means for reciprocating said slide-bar, a pressure device for forcing the heel-blank into engagement with the gouger and the front face of said slide-bar and means 30 for actuating said pressure device, said means having a common driving member and being co-ordinated to force the pressure device and heel-blank toward the slide-bar substantially simultaneously with the downward 35 movement of the latter.

5. A gouging machine comprising a support, a slide-bar mounted therein for vertical reciprocation, a gouger mounted in the slide-bar and projecting from the front face 40 thereof, a pressure device for forcing the heel-blank into engagement with the gouger and the front face of said slide-bar, a feeding device for moving a heel-blank to a position opposite said gouger, a plurality of 45 means for reciprocating the slide-bar and for actuating said pressure and feed devices, said means being co-ordinated to move the feed device to the limit of its feed movement and return the same in advance of the actuation 50 of the pressure device and to move the pressure device and heel-blank toward and in engagement with the gouger and slide-bar substantially simultaneously with the downward movement of the latter.

6. A gouging machine comprising a support, a slide-bar mounted therein for vertical reciprocation, a gouger mounted in the slide-bar and projecting from the front face thereof, a pressure device for forcing the 55 heel-blank into engagement with the gouger and the front face of said slide-bar, a feeding device for moving a heel-blank to a position opposite said gouger, a plurality of 60 means for reciprocating the slide-bar and for actuating said pressure and feed devices, 65

said means being co-ordinated to move the feed device to the limit of its feed movement and return the same in advance of the actuation of the pressure device and to move the pressure device and heel-blank toward and 70 in engagement with the gouger and slide-bar substantially simultaneously with the downward movement of the latter, and a common actuating member for causing the slide-bar, pressure device and feed device to function. 75

7. A gouging machine comprising a support, a slide-bar mounted therein for vertical reciprocation in a fixed path, a gouger mounted on said slide-bar and projecting from the front face thereof, a movable member mounted on the machine, a pressure device yieldingly mounted in said movable member, means for reciprocating the slide-bar, and means for actuating said movable member to force the pressure device toward the slide-bar, whereby a heel-blank located between the slide-bar and the pressure device will be forced by the latter with a yielding pressure against the slide-bar and the gouger carried thereby. 80 85 90

8. A gouging machine comprising a support, a slide-bar mounted therein for vertical reciprocation, a gouger carried by the slide-bar projecting from the front face thereof, means for reciprocating the slide-bar, pressure mechanism comprising a plate for forcing a heel-blank into engagement with the gouger and the front face of said slide-bar and in a direction at right angles to the plane of movement of the gouger, said 95 plate having an inclined recess in its face to compensate for the incline of a decked heel, and means for actuating said pressure mechanism. 100

9. A gouging machine comprising a support, a slide-bar mounted therein for vertical reciprocation, a gouger carried by the slide-bar and projecting from the front face thereof, a driven shaft having mounted thereon a crank and a cam wheel in fixed relation, a 105 pitman rod connecting the crank and slide-bar for causing the reciprocation of the latter, a pressure device movable toward and from the slide-bar and gouger, and means for actuating the pressure device in one direction comprising a member carried by the pressure device and having a contact member thereon in engagement with said cam wheel. 110 115

10. A gouging machine comprising a support, a slide-bar mounted therein for vertical reciprocation, a gouger mounted in said slide-bar and projecting from the front face thereof, a driven shaft having a crank and a cam wheel mounted thereon in fixed 120 relation, a pitman rod connecting said crank and slide-bar for causing the reciprocation of the latter, a pressure device pivotally mounted in overbalanced relation to its bearing and operating automatically to move by 125 130

- gravity in a direction away from said slide-bar, and means for moving the pressure device toward the slide-bar to force a heel-blank into engagement therewith and with the gouger carried thereby comprising a member pendent from the pressure device and having at its lower end a contact member held by gravity in engagement with said cam wheel.
- 10 11. A gouging machine comprising a support, a slide-bar slidably mounted for reciprocation therein, means for reciprocating the slide-bar, a gouger carried by the slide-bar and projecting from the front face thereof, a cutting-block located in a position to support a heel-blank opposite the gouger and having a cutting edge located in the plane of the cut of the cutting edge of the gouger, and means for pressing the heel-blank against said gouger and the face of said slide-bar and in a direction at right angles to the plane of movement of the gouger.
- 15 12. A gouging machine comprising a support, a slide-bar slidably mounted therein and carrying a gouger, a pivotally mounted gravity-swung pressure device for forcing a heel-blank against said gouger and slide-bar and having a contact end, a pivotally mounted spring-controlled throw-arm, carrying a contact wheel intermediate its ends, a feed-plate for moving heel-blanks into position opposite the gouger associated with said throw-arm, a driven shaft, a pair of cam members and a crank mounted on said driven shaft, and a pitman pivotally connecting said crank and slide-bar, one of said cam members being adapted to engage and release said contact wheel, and the other, 40 to engage and release the contact end of said pressure device.
13. In a gouging machine, in combination with a reciprocating gouger, a movable support, a pressure device slidably mounted in said support, a member for adjusting said pressure device mounted on said support and having a stop, and a spring carried by said member tending normally to press said pressure device into engagement with said stop.
- 45 50 14. In a gouging machine, in combination with a gouger and means for reciprocating the same, a member movable toward and from the gouger, a pressure device yieldingly mounted on said member and movable therewith to press a heel-blank into engagement with said gouger, and means for adjusting the normal position of said pressure device relative to the gouger.
15. In a gouging machine, in combination with a gouger and means for reciprocating the same, a member movable toward and from the gouger, a pressure element slidably mounted on said member for pressing a heel-blank into engagement with the gouger and having an opening, means for adjusting said element toward and from the gouger, a rod having a screw-threaded portion engaging the screw-threaded aperture in said member and having a stop and a smooth portion, the latter mounted in and passing through said opening, a head on the end of the smooth portion of said rod, and a spring located between said head and the pressure element to maintain the latter in normal engagement with said stop.
- 75 16. A machine for gouging heel-blanks comprising a support, a member slidably mounted therein and having a gouger projecting from its front face, a feeder for moving a heel-blank to a position in front of the gouger, means for actuating said feeder comprising positive means for withdrawing the feeder and automatic means for moving it in the feeding direction, means for forcing the heel-blank against said gouger and the front face of said member and in a direction at right angles to the plane of movement of the gouger, and means for imparting a vertical reciprocation to said member.
- 80 85 90 95 100 17. A machine for gouging heel-blanks comprising a support, a member slidably mounted therein and having a gouger projecting from its front face, a feeder for moving a heel-blank to a position in front of the gouger, means for actuating said feeder comprising positive means for withdrawing the feeder and a spring for moving it in the feeding direction, means for forcing the heel-blank against said gouger and the front face of said member, and means for imparting a vertical reciprocation to said member.
- In testimony whereof, I have hereunto set my hand.

DENNIS PARKS.
